UNITED STATES PATENT OFFICE.

ELI ROBIDEAU, OF MALONE, NEW YORK.

DUST COLLECTOR.

Application filed July 28, 1921. Serial No. 488,073.

To all whom it may concern:

Be it known that I, ELI ROBIDEAU, a citizen of the United States, residing at Malone, in the county of Franklin and State of New York, have invented a new and useful 5 Dust Collector, of which the following is a specification.

This invention relates to a dust collector particularly designed for use in removing 10 and retaining dust that has been gathered up by a mop.

One of the objects of the invention is to provide a container into which a mop can be inserted readily, there being a closure for 15 preventing dust from spreading outside of the container while the mop is being cleaned.

A further object is to provide rods or other abutments on which the mop can be beaten for the purpose of separating the 20 dust therefrom, a suitable receptacle being disposed within the container into which the dust will settle so that it can subsequently be removed readily.

With the foregoing and other objects in 25 view which will appear as the description proceeds the invention resides in the combination and arrangement of parts and in the details of construction hereinafter described and claimed, it being understood that, within 30 the scope of what is claimed, changes in the precise embodiment of the invention shown can be made without departing from the spirit of the invention.

In the accompanying drawings the preferred forms of the invention have been 35 shown.

In said drawings—

Figure 1 is a front elevation of the device.

Figure 2 is a section on line 2—2, Figure 40 1.

Figure 3 is a longitudinal section through a portion of a slightly modified form of structure.

Referring to the figures by characters of 45 reference 1 designates a container of any desired proportions and preferably provided on its top with a handle 2 whereby it can be carried conveniently from place to place. An opening 3 is formed in the front wall of 50 the container and is normally closed by a door 4 hingedly mounted at its upper end as shown at 5. This door has a longitudinal slot 6 extending thereinto from its lower edge and secured to the side portions or 55 walls of the slot are flaps 7 of rubber or other suitable material which tend normally

to close the slot. A drawer or other suitable receptacle 8 is mounted in the lower portion of the container 1 and is adapted to be withdrawn through an opening 9 in one wall of 60 the container, there being a handle 10 on the outer end of this drawer whereby it can be easily moved into and out of position.

Transverse rods 11 or the like are arranged within the container below the level 65 of the opening 3 and constitute means on which a mop can be beaten for the purpose of separating dust from the mop.

The door 4 is held closed normally by gravity and can be opened by means of a 70 knob 12 extending outwardly therefrom. If desired, however, the door can be of the modified construction shown in Figure 3, this modified door 13 being so shaped and proportioned as to swing within the opening 75 14 in the container 15.

In using the structure shown in Figures 1 and 2 the door 4 is swung outwardly to open position and the mop to be cleaned is inserted through the opening 3. The door is 80 then closed so that the handle of the mop will be received within the slot 6, the flaps 7 opening out so as to receive the handle between them and permit the handle to be moved about. After the door has been 85 closed the handle can be manipulated so that the mop cloth will be struck against the rods 11. Consequently dust will be beaten therefrom and will settle into the receptacle 8. The door 4 and the flaps 7, however, 90 will prevent the dust from floating out of the container into the surrounding atmosphere.

Instead of being compelled to open the door outwardly in order to insert the mop 95 the door 13 will swing inwardly when the mop is pressed thereagainst and after the mop has been properly inserted the door will gravitate to closed position so that the handle of the mop will be seated in the slot 100 in the door.

What is claimed is:—

1. A dust collector for mops including a container having an opening in one face, a door normally closing the opening and having a slot therein for the reception of a mop handle, flexible means connected to the door for closing the slot, and means supported within the container for receiving the impact of a mop. 105

2. A portable dust collector including a container, there being an opening in one wall 110

of the container, a normally closed door extending across the opening and having a slot therein for the reception of a mop handle, flexible means normally closing the slot to prevent egress of dust, and means mounted within the container for receiving the impact of a mop.

3. A portable dust collector including a container, there being an opening in one wall of the container, a normally closed door extending across the opening and having a slot therein for the reception of a mop handle, flexible means normally closing the slot

to prevent egress of dust, and means mounted within the container for receiving the impact of a mop, and a removable receptacle for receiving dust settling within the container.

In testimony that I claim the foregoing as my own, I have hereto affixed my signature in the presence of two witnesses.

ELI ROBIDEAU.
